STEAM JET REFRIGERATING SYSTEM

John E. Haines, Minneapolis, Minn., assignor to
Minneapolis-Honeywell Regulator Company,
Minneapolis, Minn., a corporation of Delaware

Application January 8, 1936, Serial No. 58,120

15 Claims. (Cl. 62—152)

This invention relates to refrigerating systems, and more particularly to that type of system which utilizes a condenser, an evaporator and an ejector for accomplishing a cooling action.

5 An object of this invention is to provide a novel means for controlling the circulation of the cooling fluid to and from the evaporator, wherein the amount of cooling fluid from the evaporator supplied to the point of use is controlled in accordance with the load on the refrigerating system.

10 Another object of this invention is to provide a novel means for controlling the supply of condensing water to the condenser wherein the amount of condensing water delivered to the condenser is controlled in accordance with the load placed on the condenser.

15 Still another object of this invention is to provide a means for controlling the operation of the steam jet ejector in accordance with the temperature of the cooling fluid returned to the evaporator, the arrangement being such that if the temperature of such cooling fluid decreases below a predetermined value the steam jet ejector is rendered inoperative.

20 A further object of this invention is to provide a control mechanism responsive to the temperature of the cooling fluid returning to the evaporator, for controlling the operation of the steam jet ejector, the operation of the vacuum producing means for the condenser and the operation of the condenser water circulating means.

25 Another object of this invention is to provide a control system embodying the above control means for accomplishing a complete, accurate, safe and efficient control of the refrigerating mechanism.

30 Other objects and advantages will become apparent to those skilled in the art upon reference to the accompanying specification, claims and drawing, in which drawing:

35 Figure 1 illustrates one form of my invention as applied to a refrigerating system utilizing a refrigerating coil located in an air conditioning unit, and

40 Figure 2 illustrates another form of my invention which utilizes a spray located in an air conditioning unit.

45 For a more thorough understanding of my invention reference is made specifically to Figure 1, wherein there is diagrammatically shown an evaporator 10 connected to a nozzle box 11, which in turn is connected by an orificed jet 12 to a condenser 13. Condensed fluid is drawn from the condenser 13 through a conduit 14 by a vacuum 50 or discharge pump 15 and delivered through a

5 pipe 16 to a boiler, not shown. Power fluid, which may take the form of steam, is supplied to the nozzle box 11 from a boiler, not shown, through a steam pipe 17 under the control of a valve 18. The valve 18 is moved to an open or closed position by a motor 19 which is well known the art. Located in the evaporator 10 is a spray 20 which is connected by a pipe 21 to a refrigerating coil 22 located in an air conditioning unit 23. The expended cooling fluid is returned from the 10 cooling coil 22 to the spray 20 by the pipe 21 in the direction indicated by the arrow. Chilled cooling fluid is drawn from the evaporator 10 through a pipe 24 by a circulating pump 25 and delivered by a pipe 26 to the refrigerating coil 15 22 in the air conditioning unit 23. The operation 20 of the steam jet refrigerating mechanism thus far described is old in the art and it is sufficient to state that when steam is supplied to the nozzle box 11 a vacuum is created in the evaporator 10 25 to flash the cooling fluid flowing from the spray 20 to cause chilling of the same and this chilled cooling fluid is delivered by the circulating pump 25 to the refrigerating coil 22 for cooling the air passing thereover.

25 Located in the pipe 26 is a valve 27 which is adapted to be positioned between open and closed position to control the amount of cooling fluid being delivered to the refrigerating coil 22. The valve 27 may be operated by a rack 28 and a 30 pinion 29 which is rotated in either direction by a proportioning motor 30 of the type shown and described in Patent No. 1,989,972 issued to Lewis L. Cunningham on February 5, 1935. The motor 30 may be suitably held in position by means of 35 a bracket 31. The motor 30 may be operated by a temperature controller generally designated at 32, which is responsive to the temperature of the cooling fluid returning to the evaporator or by a temperature controller 33 responsive to the 40 temperature of the air flowing over the refrigerating coil 22.

45 The temperature controller 32 may comprise a bellows 34 connected by a capillary tube 35 to a bulb 36 containing a volatile fluid and located in intimate contact with the cooling fluid returning to the evaporator. Upon an increase in cooling fluid temperature the bellows 34 is expanded to move a slider 37 upwardly with respect to a potentiometer coil 38. Upon a decrease in cooling fluid temperature the slider 37 is moved downwardly with respect to the potentiometer coil 38. The slider 37 is connected by a wire 39, a manual switch 40 and a wire 41 to the proportioning motor 30, and the upper and lower 50 55

ends of the potentiometer coil 38 are connected to the proportioning motor 30 by means of wires 42 and 43 respectively.

The temperature controller 33 located in the air conditioning unit 23 may comprise a bimetallic element 44 for operating a slider 45 with respect to a potentiometer coil 46. The slider 45 is connected by a wire 47, a manual switch 48 and a wire 49 to the proportioning motor and the left and right ends of the potentiometer coil 46 are connected by wires 50 and 51, respectively, to the proportioning motor 30.

With the manual switch 40 in a closed position and the manual switch 48 in an open position, as shown in Figure 1, the temperature controller 32 controls the operation of the proportioning motor 30 so that upon an increase in the temperature of the cooling fluid returning to the evaporator the proportioning motor 30 is operated to move the valve 27 toward an open position to admit more cooling fluid to the refrigerating coil 22 in the air conditioning unit 23 to increase the cooling effect of the refrigerating coil 22 on the air passing thereover. Likewise, upon a decrease in temperature of the cooling fluid returning to the evaporator the slider 37 is moved downwardly with respect to the potentiometer coil 38 to operate the proportioning motor 30 in the opposite direction to move the valve 27 toward a closed position to decrease the supply of cooling fluid being delivered to the refrigerating coil 22. Preferably the returning cooling fluid is maintained at 60°. With the manual switch 40 in an open position and the manual switch 48 closed the temperature controller 33 is placed in control of the proportioning motor 30 and upon an increase in the temperature of the air passing through the conditioning unit 23 the slider 45 is moved to the left in the direction indicated by the character H to cause operation of the proportioning motor 30 to move the valve 27 towards an open position to supply more cooling fluid to the refrigerating coil 22. Likewise, upon a decrease in temperature of the air passing through the air conditioning unit 23 the slider 45 is moved towards the right in the direction indicated by the character C to operate the proportioning motor 30 in the opposite direction to move the valve 27 toward a closed position to decrease the supply of cooling fluid to the refrigerating coil 22. In each instance the amount of cooling fluid delivered to the refrigerating coil 22 is proportioned in accordance with the temperature changes of the cooling fluid returned to the evaporator, or of the air passing through the air conditioning unit 23. Power is supplied to the proportioning motor 30 for performing the control function by means of line wires 52 and 53.

It will be seen that if the valve 27 is moved to a completely closed position, the circulation of cooling fluid through the refrigerating coil 22 would be stopped and, therefore, there would be no flow of cooling fluid past the bulb 36 of the temperature controller 32. In order to insure a continued flow of a minimum amount of cooling fluid past this bulb 36 a by-pass around the valve 27 is provided at 54. This by-pass around the valve 27 permits a small flow of cooling fluid to circulate through the cooling portion of the system so that the temperature controller 32 will be able to respond to the temperature thereof, and, therefore, respond readily to changes in temperature in the cooling fluid.

In order to prevent the building up of undue pressures in the conduit 26 a by-pass between

the conduit 26 and the return conduit 21 is provided and this by-pass includes a pressure relief valve 55 so that when the valve 27 is moved towards a closed position and the pressure builds up in the conduit 26 this excess pressure may be relieved to the return conduit 21 through the pressure relief valve 55. By reason of the construction outlined above, an extremely accurate temperature control of the cooling fluid is obtained and safe operation of the cooling portion of the refrigerating system is assured.

Referring now to Figure 2, I have shown my invention as applied to a spray 56 located in an air conditioning unit 57. Cooling fluid is delivered to the spray 56 from the evaporator 10 through a pipe 58, a three-way valve 59 and a pipe 60. The expended cooling fluid is withdrawn from the air conditioning unit 57 through a pipe 61 by a circulating pump 62 and returned by a pipe 63 to the spray 20 in the evaporator 10. A by-pass pipe 64 connects the return pipe 63 with the three-way valve 59 and the three-way valve 59 may be operated through a rack 65 and a pinion 66 by a proportioning motor 67 in all respects the same as the proportioning motor 30 of Figure 1. The proportioning motor 67 may be suitably mounted on a bracket 68 and power may be delivered to the proportioning motor 67 by line wires 69 and 70 leading from some source of power, not shown. The circulating pump 62 may be connected across the line wires 69 and 70 by wires 71 and 72, respectively. The proportioning motor 67 may be controlled by a temperature controller 73 which may comprise a bellows 74 connected by a capillary tube 75 to a bulb 76 containing a volatile fluid and located in intimate contact with the cooling fluid returning to the evaporator through the return pipe 63. The bellows 74 is adapted to operate a slider 77 with respect to a potentiometer coil 78. The slider 77 is connected by a wire 79 to the proportioning motor 67 and the upper and lower ends of the potentiometer coil 78 are connected by wires 80 and 81 to the proportioning motor 67. The arrangement is such that upon an increase in temperature of the cooling fluid returning to the evaporator, the slider 77 is moved upwardly with respect to the potentiometer coil 78 to operate the proportioning motor 67 to move the three-way mixing valve 59 toward a position where more cooling fluid is delivered from the conduit 58 and less return cooling fluid is delivered from the conduit 64 to the spray 56, whereby the temperature of the spray is decreased to increase the cooling effect of the spray. Likewise, upon a decrease in temperature of the cooling fluid returning to the evaporator, the slider 77 is moved downwardly with respect to the potentiometer coil 78 to operate the proportioning motor 67 in the opposite direction to supply more return cooling fluid and less chilled cooling fluid to the spray 56. In each instance the amount of return cooling fluid and the amount of chilled cooling fluid is proportioned according to the temperature of the cooling fluid being returned to the evaporator. In this manner, the temperature of the returning spray water is maintained at the desired value, preferably 60°.

Referring again to Figure 1, condensing fluid is discharged from the condenser 13 through a pipe 83 and is supplied to the condenser 13 through a pipe 84 under the control of a valve 85. The valve 85 is positioned between an open and closed position by a rack 86 and a pinion 87 which is operated by a proportioning motor 88.

which may be identical with the proportioning motor 30. The proportioning motor 88 may be mounted on a suitable bracket 89. Power is supplied to the proportioning motor 88 by line wires 50 and 51 leading from some source of power, not shown. The proportioning motor 88 may be operated by a temperature controller generally designated at 93. The temperature controller may comprise a bellows 94 connected by a capillary tube 95 to a bulb 96 containing a volatile fluid and located in intimate contact with the discharge fluid being discharged from the condenser 13. The bellows 94 operates a slider 97 with respect to a potentiometer 98. The slider 97 is connected to the proportioning motor 88 by a wire 99 and the upper and lower ends of the potentiometer coil 98 are connected by wires 100 and 101, respectively, to the proportioning motor 88. The arrangement is such that upon an increase in temperature of the condensing fluid being discharged from the condenser 13, the slider 97 is moved upwardly with respect to the potentiometer coil 98 to move the valve 85 towards an open position, whereby an increased supply 20 of cooling fluid is supplied to the condenser 13. Likewise, upon an increase in temperature discharging from the condenser 13 the slider 97 is moved downwardly with respect to the potentiometer coil 98 to move the valve 85 towards a 25 closed position to decrease the amount of condensing fluid being delivered to the condenser 13. In this manner, the amount of condensing fluid delivered to the condenser 13 is controlled in accordance with the load on the condenser 13 so that a substantially constant condensing action 30 is maintained within the condenser 13. Preferably, the temperature of the condensing fluid being discharged from the condenser is maintained at 106°.

40 It is apparent that at times the valve 85 may be moved to a completely closed position and in order to maintain some condensing fluid in the condenser 13 and to pass some condensing fluid past the bulb 96 when the steam jet refrigerating mechanism is in operation, a by-pass 102 is 45 provided around the valve 85. The by-pass 102 is controlled by a valve 103, which in turn is opened and closed by a solenoid 104, the arrangement being such that when the solenoid 104 is energized the valve 103 is moved to an open position. The valve 103 is maintained in an open position as long as the steam jet refrigerating mechanism is maintained in operation in a manner to be pointed out more fully hereafter, 50 so that when the steam jet refrigerating mechanism is in operation a supply of condensing fluid to the condenser 13 is assured. The by-pass 102 also renders more accurate the response of the temperature controller 93 to changes in condensing fluid temperature since it causes some condensing fluid to flow past the bulb 96.

55 This invention contemplates the use of a temperature controller generally designated at 106 which may comprise a bellows 107 connected by a capillary tube 108 to a bulb 109 containing a volatile fluid and located in intimate contact with the cooling fluid being returned to the evaporator 10 through the conduit 21. The bellows 107 is adapted to operate a lever 110 which carries a mercury switch 111, the arrangement being such that when the temperature of the cooling fluid returning to the evaporator decreases to a predetermined low value, say 58°, the mercury switch 111 is moved to a circuit breaking position. 60

65 This invention also contemplates the use of a

limit control generally designated at 112 which may comprise a bellows 113 connected by a capillary tube 114 to a bulb 115 containing a volatile fluid and located in intimate contact with the cooling fluid being discharged from the evaporator. The bellows 113 operates a lever 116 which carries a mercury switch 117, the arrangement being such that when the temperature of the chilled cooling fluid decreases to a predetermined low value, say 38°, which might cause 10 freezing up of the refrigerating system the mercury switch 117 is moved to a circuit breaking position.

15 A relay coil is designated at 119 and is adapted to control the operation of switch arms 120, 121 and 122. Upon energization of the relay coil 119, the switch arms 120, 121 and 122 are moved into engagement with contacts 123, 124 and 125, respectively, and upon deenergization of the relay coil 119 the switch arms 120, 121 and 122 are 20 moved out of engagement with their respective contacts and the switch arm 120 is moved into engagement with a contact 126, this last movement being accomplished by springs, gravity or other means, not shown. When the mercury 25 switches 111 and 117 of the temperature controllers 106 and 112, respectively, are moved to a circuit making position a circuit is completed from the line wire 52 through wire 127, relay coil 119, wire 128, mercury switch 111, wire 129, 30 mercury switch 117 and wire 130, back to the other line wire 53. This causes energization of the relay coil 119. If the temperature of the cooling fluid returning to the evaporator 10 should decrease to a predetermined value indicating that 35 no more cooling is required, the mercury switch 111 is moved to a circuit breaking position to deenergize the relay coil 119. Likewise, if the temperature of the chilled cooling fluid emanating from the evaporator 10 should decrease to a 40 predetermined low value which would indicate that the refrigerating mechanism may freeze up, the mercury switch 117 is moved to a circuit breaking position to also deenergize the relay coil 119.

45 Movement of the switch arm 120 into engagement with the contact 123 completes a circuit from the line wire 53 through wire 131, switch arm 120, contact 123, wire 132, valve motor 19 and wire 133 back to the other line wire 52. 50 Completion of this circuit causes operation of the valve motor 19 to move the valve 18 to an open position to supply steam to the steam jet ejector refrigerating mechanism. Movement of the switch arm 120 into engagement with the contact 126 upon deenergization of the relay coil 119 completes a circuit from the line wire 53, through wire 131, switch arm 120, contact 126, wire 134, valve motor 19 and wire 133 back to the other line wire 52 to cause operation of the 60 valve motor 19 in the opposite direction to move the valve 18 to a closed position to prevent the further supply of steam to the steam jet refrigerating mechanism. In this manner, the steam jet refrigerating mechanism is maintained in operation but if the temperature of the cooling fluid returning to the evaporator should decrease to a predetermined low temperature, or if the temperature of the chilled cooling fluid discharging from the evaporator 10 should decrease to a 65 predetermined lower temperature the steam jet refrigerating mechanism is shut down.

70 Movement of the switch arm 121 into engagement with the contact 124 completes a circuit from the line wire 53, through wire 136, contact 75

124, switch arm 121, wire 137, manual switch 138, wire 139, solenoid 104 and wire 140 back to the other line wire 52. Therefore, when the refrigerating mechanism is placed or maintained in 5 operation the solenoid valve 104 is energized to open the by-pass 102 to assure that condensing fluid will be circulated through the condenser 113.

Movement of the switch arm 122 into engagement with the contact 125 completes a circuit from the line wire 53, through wire 142, contact 125, switch arm 122, wire 143, electrically operated vacuum pump 15 and wire 144 back to the other line wire 52. Completion of this circuit 15 causes operation of the vacuum pump 15 to create a vacuum in the condenser 13. Therefore, when the steam jet refrigerating mechanism is placed or maintained in operation the vacuum pump 15 is operated to create and maintain a vacuum 20 within the condenser 13.

If it be desired to control the by-pass valve 103 in accordance with the movement of the steam valve 18 the manual switch 138 may be moved to an open position and a manual switch 25 148 may be moved to a closed position. Therefore, a circuit may be completed from the line wire 53, through wires 136, 146 and 147, manual switch 148, mercury switch 149 carried by a lever 150 operated by the valve motor 19, wires 151, 30 152 and 139, solenoid 104, and wire 140 back to the other line wire 52. The mercury switch 149 is tilted to a circuit making position whenever the steam valve 18 is moved to an open position to complete the above circuit. Therefore, the 35 solenoid 104 may be energized in direct response to the opening movement of the steam valve 18 so that the circulation of condensing fluid through the condenser 13 is insured when the steam jet refrigerating mechanism is placed in operation.

40 If it be desired to operate the by-pass valve 103 associated with the condensing fluid in accordance with the actual supply of steam to the steam jet refrigerating mechanism, the manual switches 138 and 148 may be moved to an open 45 position and a manual switch 154 may be moved to a closed position. These movements of the manual switches complete a circuit from the line wire 53, through wires 136, 146 and 153, manual switch 154, mercury switch 155, operated by a 50 pressure controller 156 which may comprise a bellows 157 connected by a pipe 158 to the steam pipe 17 for operating a lever 159 which carries the mercury switch 155. The circuit is continued from the mercury switch 155 through wires 160, 55 152 and 139, solenoid 104 and wire 140, back to the other line wire 52. The arrangement is such that when steam is supplied to the steam jet 60 ejector refrigerating mechanism the bellows 156 is expanded to move the mercury switch 155 to a circuit making position to complete the above 65 circuit to energize the solenoid 104 to open the by-pass valve 103 and thus insure the circulation of condensing fluid through the condenser 13 when steam is being supplied to the steam jet 70 ejector refrigerating mechanism.

From the above, it is seen that I have provided a control system for a steam jet refrigerating mechanism which provides accurate and safe control thereof. The supply of cooling fluid 75 to a point of use is accurately controlled in accordance with a demand for cooling, the supply of condensing fluid to the condenser is accurately controlled in accordance with the load on the condenser, the steam jet refrigerating mechanism is automatically placed and maintained in oper-

ation upon a demand for cooling by supplying steam to the refrigerating mechanism and by operating the vacuum creating means and the circulation of condensing fluid through the condenser 13 is assured when the steam jet refrigerating mechanism is placed or maintained in 5 operation.

Although I have disclosed for purposes of illustration various forms of my invention, other forms thereof may become apparent to those skilled in the art and, consequently, my invention is to be limited only by the scope of the appended claims and the prior art.

I claim as my invention:

1. In a refrigerating system having an evaporator, ejector and condenser, the combination of means for controlling the supply of condensing fluid to the condenser, means for circulating cooling fluid through the evaporator for chilling the same, and means responsive to the temperature 20 of the cooling fluid returning to the evaporator for controlling the condensing fluid supply controlling means.

2. In a refrigerating system having an evaporator, ejector and condenser, the combination of 25 means for supplying condensing fluid to the condenser, a valve in control of the supply of condensing fluid to the condenser, thermostatic means responsive to the temperature of the condensing fluid discharged from the condenser for 30 modulating the valve to control the condensing action of the condenser, a by-pass around said valve, a second valve in control of said by-pass, means for circulating cooling fluid through the evaporator for chilling the same, and means responsive to the temperature of the cooling fluid returning to the evaporator for controlling said 35 second valve.

3. In a refrigerating system having an evaporator, ejector and condenser, the combination of 40 means for circulating cooling fluid through the evaporator, means for controlling the supply of condensing fluid to the condenser, means for controlling the supply of power fluid to the ejector, and means responsive to the temperature 45 of the cooling fluid returning to the evaporator for controlling the condensing fluid controlling means and the power fluid controlling means.

4. In a refrigerating system having an evaporator, ejector and condenser, the combination of 50 means for supplying condensing fluid to the condenser, a valve in control of the supply of condensing fluid to the condenser, thermostatic means responsive to the temperature of the condensing fluid discharged from the condenser for 55 modulating the valve to control the condensing action of the condenser, a by-pass around said valve, a second valve in control of said by-pass, means for circulating cooling fluid through the evaporator for chilling the same, means for controlling the supply of steam to the ejector, and means responsive to the temperature of the cooling fluid returning to the evaporator for controlling the steam control means and the second 60 valve.

5. In a refrigerating system having an evaporator, condenser and ejector the combination of 65 means for circulating cooling fluid through the evaporator, means for controlling the supply of condensing fluid to the condenser, means for creating a vacuum in the condenser, and means responsive to the temperature of the cooling fluid 70 returning to the evaporator for controlling the condensing fluid controlling means and the vacuum creating means.

6. In a refrigerating system having an evaporator, ejector and condenser, the combination of means for supplying condensing fluid to the condenser, a valve in control of the supply of condensing fluid to the condenser, thermostatic means responsive to the temperature of the condensing fluid discharged from the condenser for modulating the valve to control the condensing action of the condenser, a by-pass around said valve, a second valve in control of said by-pass, means for creating a vacuum in the condenser, means for circulating cooling fluid through the evaporator for chilling the same, and means responsive to the temperature of the cooling fluid returning to the evaporator for controlling said vacuum controlling means and said second valve.

7. In a refrigerating system having an evaporator, condenser and ejector the combination of means for circulating cooling fluid through the evaporator, means for controlling the supply of condensing fluid to the condenser, means for creating a vacuum in the condenser, means for controlling the operation of the ejector, and means responsive to the temperature of the cooling fluid returning to the evaporator for controlling the condensing fluid controlling means, the vacuum creating means and the ejector controlling means.

8. In a refrigerating system having an evaporator, ejector and condenser, the combination of means for supplying condensing fluid to the condenser, a valve in control of the supply of condensing fluid to the condenser, thermostatic means responsive to the temperature of the condensing fluid discharged from the condenser for modulating the valve to control the condensing action of the condenser, a by-pass around said valve, a second valve in control of said by-pass, means for creating a vacuum in the condenser, means for controlling the operation of the ejector, means for circulating cooling fluid through the evaporator for chilling the same, and means responsive to the temperature of the cooling fluid returning to the evaporator for controlling said vacuum controlling means, said second valve and the ejector controlling means.

9. In a refrigerating system having an evaporator, ejector and condenser, the combination of means for circulating cooling fluid between the evaporator and a point of use, a valve in control of the flow of cooling fluid to the point of use, means for controlling the operation of the ejector, and means responsive to the temperature of the cooling fluid returning to the evaporator for controlling the valve and the ejector controlling means.

10. In a refrigerating system having an evaporator, ejector and condenser, the combination of means for circulating cooling fluid between the evaporator and a point of use, a valve in control of the flow of cooling fluid to the point of use, means for creating a vacuum in the condenser, and means responsive to the temperature of the cooling fluid returning to the evaporator for con-

trolling the valve and the vacuum creating means.

11. In a refrigerating system having an evaporator, ejector and condenser, the combination of means for circulating cooling fluid between the evaporator and a point of use, a valve in control of the flow of cooling fluid to the point of use, means for controlling the supply of condensing fluid to the condenser, and means responsive to the temperature of the cooling fluid returning to the evaporator for controlling the valve and the condensing fluid control means.

12. In a refrigerating system having an evaporator, ejector and condenser, the combination of means for controlling the circulation of cooling fluid between the evaporator and a point of use, means for controlling the operation of the ejector, means for controlling the operation of the condenser and means responsive to the temperature of the cooling fluid returning to the evaporator for controlling the cooling fluid controlling means, the ejector controlling means and the condenser controlling means.

13. In a refrigerating system having an evaporator, ejector and condenser, the combination of means for controlling the circulation of cooling fluid between the evaporator and a point of use, means for controlling the operation of the ejector, means for controlling the supply of condensing fluid to the condenser, means for creating a vacuum in the condenser, and means responsive to the temperature of the cooling fluid returning to the evaporator for controlling the cooling fluid controlling means, the ejector controlling means, the condensing fluid controlling means and the vacuum creating means.

14. In a refrigerating system having an evaporator, ejector and condenser, the combination of means for controlling the supply of condensing fluid to the condenser in response to the temperature of the condensing fluid leaving the condenser, means for controlling the circulation of cooling fluid from the evaporator in response to the demand for cooling, and means responsive to the temperature of the cooling fluid returning to the evaporator for controlling the operation of the ejector, the vacuum in the condenser and the supply of condensing fluid.

15. In a refrigerating system having an evaporator, ejector and condenser, the combination of means for controlling the supply of condensing fluid to the condenser in response to the temperature of the condensing fluid leaving the condenser, means for controlling the circulation of cooling fluid from the evaporator in response to the demand for cooling, means responsive to the temperature of the cooling fluid returning to the evaporator for controlling the supply of steam to the ejector and for controlling the vacuum in the condenser, and means responsive to the supplying of steam to the ejector for additionally controlling the supply of condensing fluid to the condenser.

JOHN E. HAINES.
